UNITED STATES PATENT OFFICE

ROLLAND JOSEPH GAZELLE, OF MONTREAL, QUEBEC, CANADA

TANK CONSTRUCTION

Application filed February 8, 1928, Serial No. 252,810, and in Canada March 4, 1927.

The present invention relates to improvements in the combination of a water heater with a tank, and the main object of the invention is to provide a heat insulated tank 5 of neat appearance, strong and of compact construction, and of high efficiency, due to its peculiar construction which eliminates all loss of heat.

A further object of the invention is to provide a heater and tank of this character, that 10 will be simple and cheap of construction and so constructed that easy access will be had to the electrical connections, and heating units.

The invention is hereinafter fully described in the following specification and illustrated in the accompanying drawings, in which:—

Figure 1 is a longitudinal sectional view through a water heating tank according to 20 the invention.

Figure 2 is an enlarged segmentary longitudinal sectional view through a slightly modified form of the invention.

Like numerals of reference indicate corresponding parts in each figure.

Referring to the drawings, 1 is the main water tank, provided with the usual water inlet pipe 2, and the hot water outlet pipe 3 which is about one inch longer, at the top of 30 the tank 1 than the said inlet pipe 2, and 4 is the return pipe. 5 are the heating unit casings connected to the cold water inlet supply pipe 2^a, and to the inlet pipe 2 which projects into said water tank 1. In each of said heating unit casings 5 is placed an inner casing carrying its heating element 6. 7 is an intermediate or central superposed casing or tank, the inner side of which is nickel plated to reflect the heat rays back on the main water 35 tank 1, and 8 is a frame upon which is suitably secured the said central tank 7, also supporting the main water tank 1, said frame 8 being also supported and secured to the main frame 9 which is provided with the stand- 40 ards 10. On said main frame 9 is mounted the outer superposed open end casing 11, the inner side of said casing being lined with galvanized tin 12. The main object is to 45 strengthen same, and keep the outer cold air from reaching said main tank 1. Each of

said superposed tanks are preferably spaced from one another as disclosed in the drawings.

The water tank 1 is insulated from the center tank 7 by a lining 13 of asbestos or the like, and 13^a is another asbestos lining provided to insulate the frame 9 from said center tank. The main object in providing these asbestos linings 13 and 13^a, is to prevent the cold air from reaching the bottom of said main water tank 1. The frame 9 is provided with an apron 14 which encloses the heating units 5. In the apron 14, is provided an opening 15 through which passes the hot water pipe 3, and 16 is a tap valve connected 60 on the outer end of said pipe.

It will be readily seen with the aid of the present description and drawings, that the tank is of simple construction and that if the heating elements should burn out, easy 70 access may be had to said heating elements without disconnecting the water connections, and consequently, the cost of repairing same is reduced to a minimum. I also wish to make it clearly understood, that modifications may be made in the construction of said tank, providing they fall within the scope of 75 the following claims for novelty.

What I claim as my invention is:

1. A water tank of the character described, 80 comprising a main tank, an inlet and outlet pipe connected thereto, an intermediate tank enclosing said main tank and suitably distanced therefrom, means on the inner surface of said intermediate tank to reflect the heat rays radiating from said main tank, an insulating lining located between the bottoms of said tanks, a frame for supporting said tanks, an insulating lining located between said intermediate tank and said frame, and 90 an outer open and superposed casing enclosing said intermediate tank, suitably distanced therefrom and supported upon said frame, substantially as described.

2. A hot water tank comprising a main 95 tank, an intermediate tank enclosing said main tank and suitably distanced therefrom, means on the inner surface of said intermediate tank to reflect the heat rays radiating from said main tank, an insulating member 100

located between the bottoms of said tanks, and an outer superposed casing enclosing said intermediate tank and suitably distanced therefrom.

5 3. A hot water tank comprising a main tank, a casing surrounding said tank, the inner surface of said casing having a surface adapted to reflect heat rays radiating from said tank, and a heat insulating member
10 between the bottom of said casing and the bottom of said tank.

Signed at Montreal, Quebec, Canada, this
19th day of January 1928.

ROLLAND JOSEPH GAZELLE.
